CONTAINER

Duryea Bensel, Beechhurst, Long Island, N. Y.,
assignor to Bensel Corporation, a corporation of
Delaware

Application September 28, 1933, Serial No. 691285

28 Claims. (Cl. 229—55)

One object of the present invention is to provide an inexpensive self-complete container which, while seamless all over except for a single closing seam, can be hermetically sealed at said seam and can properly package any wet or dry product, and which, at the same time, although including a single substantially rectangular blank folded in a way to make the container a satchel-type one, is built up from a plurality of blanks of such dissimilar physical qualities and so interfolded one with another as to insure that said single seam provides the aforesaid seal while establishing the filled container as a self-sustaining one. By a self-complete container is meant one which is the entire packaging structure to be delivered to the purchaser of the product in such container; and by a self-sustaining container is meant one which, when folded up and seamed closed after being filled with such product, will withstand, without weakening at or damage to said seam and without breakdown anywhere, such pressures and impacts as a filled carton of the side-seamed type as ordinarily made from pressboard of the commonly used thicknesses or weights is normally subjected to incidental to transportation and other handling.

A container as above described is provided, according to the present invention, by interfolding a heavier blank, hereinafter called the builder sheet, and a lighter blank, hereinafter called the sealer sheet, and so differentially shaping these two sheets and so relating them as to their interfoldings that while both sheets coact to establish the single closing seam and to make the latter a hermetically sealed one, the builder sheet at the same time acts as the "backbone" of the container because by its inclusion in the combination it insures that the container shall be a self-sustaining one. Others in the art have proposed taking a substantially rectangular blank of thin waxed paper or the like and folding the same to provide a satchel-like envelope having but a single seam at the top; such blank being folded to provide a rectangular bottom wall, two rectangular side walls, and two rectangular end walls having inwardly directed flutings or pleatings in their upper portions so that when the envelope is completed it is substantially triangular in end elevation, and also four triangular two-ply web components folded up from the four corner portions of the blank and laid parallel with said side walls. These foldings are features of that embodiment of the container of the present invention herein illustrated; that

is, both the builder sheet aforesaid, and a lighter and more freely flexible blank, the sealer sheet aforesaid, are given such foldings, as well as other special ones, not only to have said container built up of one satchel-shape structure within another, but to provide all the advantages of the invention including those hereinabove stated.

Among other objects of the invention, beyond the provision of a self-sustaining and hermetically sealed container folded up from a plurality of blanks so as to be seamless all over except at such seal, are (a) to provide a top seam structure in an otherwise seamless container such that an element of said seam structure can be practically and quickly severed along a part of the seam length, but without causing or endangering a breakdown of the container, to facilitate convenient dispensing; (b) to provide container portions which, following such a severing, are easily and safely transformable into an ideal pouring spout to assist in such dispensing, not only without causing a breakdown of the container but without having to be freed for such transformation as the result, during or ancillary to such severing, of bodily removing any part of said seam structure or of otherwise modifying the relation of said seam structure to the side walls of the container except by dividing said seam structure, along the line of said severing, into substantially similar seam-structure halves; (c) to provide an arrangement of parts such that a handle or pull device for facilitating formation of said pouring spout can be permanently attached to the container yet in a manner to avoid breaking the airtightness of the container where said device is attached thereto; (d) to provide a seam structure so constituted that following a severing along a length thereof as above, and following formation and use of the spout for dispensing and a restoration of the spout-forming parts to their original condition, the severed seam parts automatically act to exert a resilient thrust toward each other to close the opening at the top of the container; and (e) to provide a simple and efficient means readily manipulable positively to seize the severed seam parts and squeeze them flatwise together to reclose the top opening in the container in an air-tight or at least a dust-tight manner.

In certain aspects thereof, particularly so far as is concerned the provision of a container of satchel-type which is nevertheless self-sustaining, the present invention, among other things, has to do with improvements on or variations from cer-

tain constructions disclosed and claimed in my copending application Ser. No. 676,806; and in certain other aspects thereof, particularly so far as are concerned the objects (a), (b), (c), (d) and (e) set forth in the paragraph immediately hereinabove, the present invention, among other things, has to do with improvements on or variations from certain constructions disclosed and claimed in my copending application Ser. No. 10 683,733.

As brought out by certain of the appended claims, the invention can also be carried out in various other ways (as will be hereinafter explained in detail); but the present invention 15 will be most clearly understood, and the various objects and advantages thereof most fully appreciated, from the following description of a preferred embodiment of the invention as shown in the accompanying drawings,—these drawings 20 illustrating a carrying-out of the invention by the use of two substantially rectangular blanks, one of which is a heavier and stiffer builder sheet and the other of which is a relatively light and flexible sealer sheet, and with the sealer sheet 25 acting as a liner for the completed container.

In said drawings,

Fig. 1 is a top plan view showing the builder sheet, and, overlying the same, the sealer sheet, these parts being arranged for folding as though 30 a single blank according to the fold lines shown on the builder sheet in broken lines and on the sealer sheet in dotted lines;

Fig. 2 is a somewhat enlarged perspective view of the left half of Fig. 1, showing these sheets in 35 course of being folded up to form a container according to the invention;

Fig. 3 is a side elevation of such container completely folded up but with the top sealing seam not yet completed—with certain internal folds 40 indicated in broken lines, or, where the near side wall of the container is shown broken away, in full lines;

Fig. 4 is an end elevation, looking toward the left in Fig. 3;

Fig. 5 is an enlarged detail, showing certain 45 parts as seen in Fig. 4, but with the top seam structure completed;

Fig. 5a is a fragmentary view similar to Fig. 5, but drawn to a different scale and exaggerated 50 for clarity, with some of the parts in greater detail;

Fig. 6 is a view similar to Fig. 5, but showing a modified seam structure;

Fig. 7 is a fragmentary perspective view, showing 55 a seam structure as in Fig. 5, a severing indicium thereon, and an auxiliary closure device carried by and slideable along the seam structure;

Fig. 8 is an enlarged perspective detail view, showing the parts at the left end of Fig. 7, and 60 showing these parts sprung apart following a severing through an element of the seam structure along the length of said indicium;

Fig. 9 is a view similar to Fig. 8, showing the 65 parts of this view and of Fig. 7, and showing a rearrangement of parts to form the pouring spout;

Fig. 10 shows said auxiliary closure device in end elevation;

Fig. 11 shows the same in bottom plan; and

Fig. 12 is a fragmentary diagrammatic view of 70 a modification of the invention which will be fully explained later herein.

Similar reference characters refer to similar parts throughout the several views of the drawings.

Referring now in detail to that particular and now preferred embodiment of the invention selected to be shown to illustrate the invention in the accompanying drawings, a sealer sheet 15 which is strictly rectangular is employed in combination with a builder sheet 16 which is only substantially rectangular. The sheet 16 includes a main body portion of strictly rectangular shape except that at each of the four corners thereof there is a square notching 16a; this main body 10 portion having an integral tab or flap 16b offset from a central length of one of its sides. The sealer sheet is longer and wider than said main body portion of the builder sheet 16, so that when the two sheets are arranged one above the other 15 as shown in Fig. 1 the marginal portions of the sealer sheet along all the four sides thereof extend beyond all the four sides of the main body portion of the builder sheet, without break or interruption all around said main body portion. 20

These two sheets are arranged and held in the relation shown, desirably by adhesively attaching the two sheets together all over their contacting areas, so that they can be folded up together as a single blank along the fold lines shown in light 25 dotted lines and in light broken lines in Fig. 1.

It is now recommended that the builder sheet 16 be made of pressboard of about the thickness or weight used for the making of the present-type six-sided side-seamed cartons for packaging 30 one or several pounds of dry food products for delivery by the retail grocer to his housewife customer; although lighter or heavier types of pressboard can be used, and, indeed, any sheet material of the proper stiffness and strength, especially if a paper-pulp one. As to the sealer sheet, it is now recommended that the same be made of Cellophane, or hydrated cellulose, or some other relatively light-weight, thin, air-tight, tough yet freely flexible and smoothly surfaced substitute, 40 or another substitute suitable for the purpose—such, for instance, at least in certain cases, as where high resistance to softening or other deterioration from moisture is not important, thin parchmentized paper. If the two sheets 15 and 45 16 are to be adhered to each other before folding, either above or otherwise, and by an applied adhesive, such adhesive may be any suitable one; very satisfactory results having been obtained when said adhesive was a cellulose paste or 50 lacquer where the sealer sheet was of Cellophane and the builder sheet was of pressboard.

These sheets 15 and 16 are folded up, simultaneously and as though one blank, at both sides of Fig. 1, as shown in connection with the left side 55 thereof in Fig. 2; from which it will be seen that as these foldings are further completed, a satchel-type container will be fully formed, as clearly shown in Figs. 3 and 4. During these foldings, the sections A, B, C, D and E of Fig. 1 become 60 respectively, the bottom wall, the two side walls, and the two end walls of the container. The parts of the sheets lying between sections B, E, C and D are bisected by diagonal fold lines F, G, H and I into four pairs of triangular sections f 65 and f', g and g', h and h' and i and i'. During folding up of the container, each of said pairs becomes a two-ply triangular web component capable of being arranged parallel with and along-side the side walls B and C; and the sheets 15 and 16 are so folded that said web components are extended within the container and between the side walls B and C. Note the diagonal fold lines I and H and the web-component sections i and h' as seen through the broken-away side wall C 75

in Fig. 3. The end walls D and E of the container are, as seen best in Fig. 4 in the case of end wall E, substantially triangular; this resulting from the fact that each such end wall is given an inwardly directed single fluting or pleating at its top by being folded along the line shown at d' or e' in Fig. 1, in course of forming the container. Such top fluting in the end wall D is clearly seen in Fig. 2. In Fig. 4, the fold line e' is seen; and in Fig. 3, both the fold lines d' and e'. As the parts are viewed in Fig. 2, as will be obvious from a comparison of Figs. 1 and 2, the side wall C is much fore-shortened, in order to make the showing of Fig. 2 as little confusing as possible.

As to the four notchings 16a of Fig. 1, both the boundaries of each thereof, one such boundary running horizontally and the other running vertically in each notching as the parts are seen in Fig. 1, become vertical, and aligned transversely of the container, when the latter is completed. Note in this connection the upper of the two notchings 16a of Fig. 2. These notchings are desirable if not essential, in every case where the height of a side wall of the container is greater than twice the length thereof, to prevent the upper inner ends of the aforesaid web components of the builder sheet 16 from overlapping longitudinally of the container; as it has been found that such overlapping will make difficult if not prevent the formation of an always dependable hermetical seal at the top seam of the container. As such notchings are shown in Fig. 1, they are so made that their vertical and horizontal boundaries will all meet, when the container has been formed, in a single plane perpendicular to the length of the container—thus providing linear rather than point abutments for the web components at each side of the container, a feature most advantageous in augmenting the strength of the container and its top seam structure. Also desirably, such notchings are all of the same size, so that the plane just-mentioned will be located at a central point along the length of the container; these notchings are so shown in Fig. 1, and, consequently, their eight boundaries are all properly indicated in Fig. 3 by the line 16a of that view.

Beyond the notchings 16a of the builder sheet 16, the sealer sheet 15 has all four of its diagonal fold lines continued up to the four corners of said sealer sheet, as indicated in dotted lines in Fig. 1, as shown in full lines in Fig. 2, and as made clear by the broken lines 15k of Fig. 3. The marginal portions of the sealer sheet, all around the entire periphery of said sheet and beyond the main body portion of the builder sheet, are finally arranged as shown in Figs. 3 and 4; and in Figs. 3 and 4 these marginal portions are still unbroken and continuous, exactly as they were with the two sheets in unfolded condition as in Fig. 1—although now various overlapping (due to the various foldings of the sealer sheet in agreement with the foldings of the builder sheet as per the dotted-line indications in Fig. 1 on the marginal portions of the sealer sheet), all around the top mouth of the container, whether such mouth be closed preparatory to establishing the top seam structure, as in Fig. 3, or opened sufficiently to fill the container with its appointed product.

Just preparatory to sealing the container after it has been filled with said product, the parts are arranged as in Fig. 4. To seal the container and establish the seam structure including such seal, a suitable adhesive, as a cellulose paste or

lacquer, is applied to the side of the flap 16b which faces the marginal portions of the sealer sheet 15 now upwardly protruding from the mouth of the container, and then said flap and said marginal portions of the sealer sheet are bent down and over the crest line of the container as shown in Figs. 5 and 5a; said flap being drawn very taut and said marginal portions being not only bent sharply over said crest line but forcibly and tightly compressed together at and beyond said crest line, and these parts being held in these relations until the adhesive has set—all by the aid preferably of a suitable power press and co-adjuvant means of proper design forming no part of the subject-matter of the present application. There is thus provided a seam structure powerfully laterally compacted, along its entire length, of a plurality of plies of sheet material including, in addition to said flap 16b and the upper marginal portions of the sealer sheet 15, the upper parts of said side walls B and C, the upper parts of both plies of all the web components and these last between said walls B and C, and the inwardly directed flutings at the tops of end walls D and C; and at the same time a seam structure including a tight seal for the container. Nevertheless, said seam structure and seal can be easily broken when desired, without any danger of breakdown of the container; and said seam structure can be easily partially broken without any danger of breakdown of the remainder thereof. The seam structure shown, it will be noted, is composed of a pair of substantially duplicate sets of plies, each such set combining to form a seam-structure half running longitudinally of the top of the container and stiffly upstanding from the side wall B or C immediately therebelow; while these seam-structure halves further herein-after referred to are bound together into a single stiffly upstanding seam-structure unit of the same length as the container merely by the single fairly light weight flap 16b of easily severable material. Also, upon severing said flap for a part of its length to facilitate dispensing of the contents of the container, the seam-structure halves thereby partially freed for divergence as hereinafter explained remain stiffly upstanding and relatively immovable ply-collections each constituting a means for interlocking the side walls B and C immediately therebelow and all parts of the container with the unsevered part of the seam structure.

The new container, as delivered to the purchaser of the same, and its contents, and even after a partial severing as above of the top seam structure, is not only self-sustaining but of really surprising strength. The top seam structure is really a relatively massive and stiffly upstanding rigidifying rib extending along the entire length of the crest line of the container, even when containing no metal elements, as is preferred; said seam structure being so formed and located as to coact in a very important way with the inserted web components and the various other folded parts of the container and their relative inclinations to make the entire container resistant to the slightest damage from the most severe external pressures and blows. As already indicated, arranging the web components within the container, that is, between the side walls B and C rather than exterior thereto, increases greatly the ruggedness of the container and the seam structure, insures a tighter seal at the latter, and gives a more attractive package.

In any such container, however strong and

rugged it be as a self-sustaining one, a single fairly light-weight pressboard flap, as the flap 16b, is all that need be relied on, as already stated, not only finally to establish the important 5 relatively massive and rigidly vertically upstanding stiffener rib at the top of the container, but also tightly to seal the container by coaction as above described with the marginal portions of the sealer sheet 15 protruded above the top edges 10 of the container side and end walls as provided by the builder sheet 16 and with said edges. Even with the flap 16b of fairly light-weight pressboard, the coaction of all the parts is such that accidental breakdown of the seam-structure 15 is well-nigh inconceivable. Yet, if it be desired to dispense from the container by way of an end opening at its top, which is particularly desirable in the case of certain products, the top seam and seal can be deliberately broken 20 along an end length thereof, merely by upthrust of a knife inserted in the inwardly directed pocket established by the top pleating of an end wall D or E—easily and quickly because the resistance offered to the cut being made by the 25 knife edge is comparatively slight, and safely because amply withstood by the container due to the self-sustaining character thereof and of the seam structure. Such cut, being between the aforesaid halves, may be continued from end to end of the seam, to provide a completely open top mouth. To the wielder of the knife, say an ordinary and not particularly sharp kitchen knife, this resistance is hardly felt, even though the knife edge has to go through several 30 plies of the sealer sheet 15 as well as through the flap 16b.

Although as shown said flap 16b is integral with the builder sheet 16, of course a suitable substitute, in the form of a single pressboard flap 40 separate from the blank 16, or one otherwise constituted than as a single ply member, can be employed.

Referring to Fig. 6, such a single but substitute flap is shown, for example, as being in the 45 form of a separate strip 16', of pressboard or other suitable sheet material (and a material readily severable or not, according as the container to which it is applied is intended to be opened for dispensing either at an end of its stop seam structure or elsewhere). Such strip 16', as long as the top of the container, is applied inverted U-fashion to complete the seam structure as shown in Fig. 6 and according to the principle of the invention as above explained, 50 after being coated on its inner surfaces with an adhesive of the kind already explained or otherwise suitable to bond the strip, of whatever material it be made, in place as the crown-piece for the completed seam structure. The marginal folded portions of the sheet 16, represented 55 as a single fold in Figs. 5 and 6, are illustrated, in greatest detail in Fig. 5a. Where such strip is not integral with the builder sheet, the latter can have an outline merely corresponding to 60 that of the main body portion of the blank 16 of Fig. 1.

In carrying out the invention, the sealer sheet can be the wrapper sheet relative to the builder sheet, as well as the liner sheet therefor, as has 65 been described and as illustrated in the drawings. All the advantages of the invention will be obtained in either case. It is recommended that the sealer sheet be the liner sheet where the container is packed with a wet product, especially when the builder sheet is such a rather absorbent

material as pressboard; but where the container is packed with a dry product, it is recommended that the sealer sheet be the wrapper sheet, to increase the attractiveness of the container. Also, of course, it is within the invention to employ two sealer sheets, one as a wrapper and the other as a liner for the builder sheet. 5

As shown in Figs. 7 to 11, the new container includes features which are very valuable where the container is packed with a dry food product 10 of free flowing character, such, for instance, as tea, coffee, sugar, salt, prepared breakfast foods, and so on, or with a wet food product such as milk a partial dispensing of which from time to time may also be desired. As has already been 15 explained, the top seam of the container can be broken along an end length thereof very quickly and easily and safely by an ordinary knife. In Fig. 7, the flap 16b is shown as having a printing or other indicium 17 extending 20 along the crest line of the seam structure and throughout an end length of the latter overlying the pocket at the fluting at the upper end of end wall D. When a kitchen or other knife, cutting edge uppermost, is inserted in said pocket 25 to the depth permitted by the upper portion thereof, and an upcut is made with said knife, the seam structure is opened by a clean cut along the length of the indicium 17, but the seam structure is not otherwise damaged or anywhere weakened beyond dividing it cleanly longitudinally in half along the cut. But now these seam-structure halves can be readily diverged, as shown in Fig. 8. Thereupon, the pleating at the top of the end wall D is freed for pull-out reversal to form 30 a pouring spout as shown in Fig. 9. To facilitate such pull-out, this pleating is shown as provided at 18 with a pull device or handle here comprising a thin string or cord 18 knotted at 18' and projecting through a suitable aperture in end 40 wall D near the fold line d'. The string 18, just ahead of the knot 18', can be fitted tightly in said aperture, and, if the contents of the container are such that the latter should be tightly sealed at said aperture, the aperture can 45 be closed and the string locked in place therein in any desired way, for instance, by applying to the string just beyond the outer end of said aperture a gob of some suitable adhesive, such as a cellulose paste or lacquer, which, upon setting, will lock the string in the aperture and at the same time plug up the latter. Such a sealing of said aperture can be dispensed with, even where the container must be tightly sealed at the point of emergence of the string therefrom, 55 in any container wherein a sealer sheet is a liner for the builder sheet and the knot 18' lies between these two sheets last-mentioned. Although a knotted string is now preferred as the pull-out device or handle for the pouring spout, 60 any other suitable pull-out device which is practicable can be substituted therefor; but when the same, or an attaching means therefor, pierces or passes through one or more apertures in the builder sheet, such aperture or apertures can be 65 prevented from breaking the seal of the container, wherever that prevention is important, by an arrangement such as one of those last described.

In Figs. 8 and 9, a sealer sheet as a liner is 70 assumed to be present, to have all the views of the drawings agree. However, in these Figs. 8 and 9, the showing has been made as though such sealer sheet is absent, in order to make these views as clear as possible.

As soon as a desired dispensing by way of the spout of Fig. 9 has been had, and the pleating at the top of end wall D has been again reversely folded toward its normal condition as shown in Fig. 4, there is an important snapping action of the parts, particularly if the builder sheet be folded up from pressboard or an equivalent material as above described; that is, the side walls B and C spring back into parallelism along the line of the cut in the seam structure, thereby automatically insuring a closing of the container top in at least a dust-tight manner.

In order positively and even more securely and tightly to close the opening in the container top, following the spring action just explained, a temporary closure device is provided, preferably as shown in Figs. 7, 9, 10 and 11, of a kind to be carried by the seam structure for sliding therealong. This is a U-shaped clip 19, preferably of light-gauge spring metal, as sheet tin. The indicium 17 is specially useful in acting as a warning signal that this clip 19 should be so positioned on the seam structure, that is, beyond the inner end of such indicium, during the cutting of the seam by an upcut of a knife edge as above described. A sliding closure of the type illustrated by clip 19 is exceedingly practicable, and is now preferred. Following an arrangement of the parts as shown in Fig. 9, and following a partial dispensing by way of the spout thus created, and following a reversal of these parts to the condition shown in Fig. 8 and the then occurring automatic closing of the container top, the clip 19, which is here shown as having a roughened gripping surface at a side thereof, is instantaneously smoothly slidable along the seam structure and toward the left in Fig. 9 so as to straddle the entire length of the severed length of the seam structure and very tightly close the opening therein and hold the latter thus closed until the next dispensing is desired. At that time, said clip has merely to be slid along the seam structure in the opposite direction and until it is beyond the inner end of the indicium 17. As between a sliding closure, and a pivoted or rotatable one (such, for instance, as shown in my aforesaid application Ser. No. 683,733), the former has as one unique advantage that there is no necessity for sending a pivoting rivet or grommet through the seam structure or any other part of the container. A sliding closure, also, is generally easier to manipulate, particularly for temporarily closing the top opening in the seam structure after a partial dispensing of the contents of the container. The clip 19 or an equivalent may be variously slidably attached to the seam structure to avoid any chance of accidental loss thereof, for instance, by longitudinally slotting one of the side extensions thereof and sending through the seam structure a rivet or the like to engage such slot, or by giving such a side extension of the clip an inwardly directed projection movable along a score line or other longitudinal indentation at a side of the seam structure. However, it is now preferred to provide a clip equipped with means against accidental loss thereof, as here shown; that is, having an edge portion 19' along the bottom of one of its side extensions bent inwardly and upwardly through 180 degrees to provide a shoulder to contact with and ride along under the under edge 16b' of the flap 16b, and having the ends of both of its sides at their bottoms outwardly canted or curled slightly as shown to facilitate smooth sliding of the clip in either direction along the seam struc-

ture, these cantings or curlings being marked 19" in Fig. 11.

When the container of the present invention is employed for the packaging of lubricating oil and other products where the contents of the container are to be advantageously dispensed at one time, one or more of the features hereinabove described in connection with Figs. 7 to 11 may be omitted. That is to say, there are included within the invention the new container as illustratively embodied in Figs. 1 to 4, and 5 or 6, in and of itself, as highly advantageous for the packaging of lubricating oils and other products where the contents of the container are dispensed at one time, either by cutting the top seam structure or by cutting away some other part of the container in such a way, for instance, as to prevent fraudulent substitution of the ordered goods; and also such container in combination with one or more of the features illustratively embodied in the container according to Figs. 7 to 11. And in the former case, in order further to prevent such fraudulent substitution, the seam structure can be made non-severable in any suitable way, as by crimping a metallic U-clip thereon in a way to prevent its removal without destruction, either as a substitute for or an addition to such a flap as that shown in Fig. 5 or 6.

Referring finally to the modification of the more or less diagrammatic view of the Fig. 12—30 which illustrates portions of a pair of builder and sealer sheets of a certain type, the former marked 16j and the latter 15j—it is pointed out that the container of the present invention can be provided of any relative dimensions as to 35 length, height and thickness such length being the dimension of the side walls, from end wall to end wall. As to the aforesaid web components of the builder sheet, these can always be folded up and laid against the side walls of the container, if with greater and greater diminution of the length of said side walls as compared to the height thereof, the corner notchings of the builder sheet are correspondingly increased in size. As to the sealer sheet, this also can always be 40 adapted to any desired relation between the height and length of the side walls of the container, and without corner-notching or cutting away said sealer sheet anywhere; this simply by giving extra foldings to the four corner portions 45 of the sealer sheet where the latter project so far beyond the corner notchings of the builder sheet that they would otherwise extend beyond the end limits of the container. In these connections, note in Fig. 12 that the blank portions 50 there shown include a side wall C' much greater in height, or vertically, than in horizontal length or between the end wall structures. Nevertheless, it is clear that the web-component sections m and m' of the builder sheet can be folded 55 pursuant to the invention to lie as shown at m'', and to have the boundaries b and b' of their notching align at b''; and that although the sealer sheet shown would have to be folded about such a long diagonal line as that extending between the points o and o', equal in length to the diagonal line p—p', this apparent difficulty is 60 easily taken care of by further folding the sealer sheet, after folding it along the line o—o', simultaneously along the lines q—r and q—s, thereby 65 accommodating the sealer sheet to the end limits of the container by throwing the point p' to the location p''.

The sealer sheet may possibly in certain cases be present as several sheet portions, overlapped 70

or overlapped and secured together; but in most if not all cases it is desirable if not essential, and it is certainly recommended, that such sealer sheet be a single integral sheet.

5 I have made particular reference hereinabove, in the statement introductory to the short description of the views of the drawings, that, as brought out by certain of the appended claims, the invention can also be carried out in various ways other than those illustrated in such drawings. Certain of the variations thus alluded to are mentioned in the paragraph immediately preceding. Whenever herein a hermetical seal is referred to, there is meant either truly such a seal, or one which is at least liquid tight or tight against the filtering therethrough of very minute- 10 ly pulverized material.

20 Although I have hereinabove indulged in considerable particularities of description, as to materials, shapings, foldings, fitments and other elements, it is to be emphasized that these are for purposes of illustration merely and to express present preferences, and not intended to be made by way of limitation except as incorporated in the 25 appended claims. The scope of protection contemplated is to be taken solely from said claims, interpreted as broadly as is consistent with the prior art, and in accordance with the essentials of the present invention as hereinabove indicated.

30 I claim:

35 1. A self-sustaining container folded up from a plurality of blanks one of which is a heavier builder sheet and another of which is a lighter sealer sheet, said builder sheet including a main body portion of substantially rectangular shape and said sealer sheet being of similar shape but larger than said main body portion and laid thereagainst to present marginal portions of the sealer sheet beyond peripheral edges of said main 40 body portion; both said sheets being folded up as though a single blank along vertical fold lines, horizontal fold lines and diagonal fold lines to form a satchel-type container having end walls inwardly pleated at their tops and closed all over except for a filling mouth along the top length thereof; certain of said fold lines throwing sections of the builder sheet to establish a two-ply web component between each end of an end wall and the adjoining side wall; these web components lying alongside the side walls so that the upper portions of all said walls and of said web components are all brought together to form a rigidifying rib coextensive with said mouth; the marginal portions of the sealer sheet projecting above said mouth all along the length thereof and being bent down over one side of said rib; and there being a closing flap overlying the top of said mouth and rib and secured to said rib to hold said marginal portions downbent as afore- 55 said and to bind all the parts of the rib into a single structure stiffly upstanding along the top line of the container and with all the component parts of such single structure relatively immovable.

60 2. The container defined in claim 1, wherein the builder sheet is notched at corners thereof but the sealer sheet is unnotched at the corners thereof corresponding to the notched corners of the builder sheet.

70 3. A blank structure for the folding therefrom of a satchel-type container having a rectangular bottom and similar side and end walls with said end walls inwardly pleated at their tops to make the container substantially triangular in end elevation and with the four corner portions of said

blank structure bent along three inwardly converging fold lines to establish four two-ply web components to lie alongside the side walls; said blank structure including a builder sheet of heavier material, and a sealer sheet of lighter 5 material; the sections of the builder sheet to form the walls aforesaid and the web components aforesaid combining to present a substantially rectangular outline, and the sealer sheet being of similar but larger outline and being folded with 10 the builder sheet while held to have its marginal portions projecting beyond the four sides of the rectangular outline first-mentioned.

4. A satchel-type self-sustaining container folded up from a substantially rectangular blank 15 of a comparatively stiff and somewhat resilient material such as pressboard to have side walls mutually converging toward the top line of the container, end walls each having an inwardly directed fluting at its top, and substantially triangular two-ply web components extended along- 20 side said side walls; said container having means for sealing the same along said top line thereby to couple tightly together the upper portions of said flutings, said side walls and said web components to make a rigidifying rib structure for the 25 container including a closing seam therefor; said sealing means including a sealing element readily severable along said line, by inserting a knife within such a fluting from the exterior of the 30 sealed container and by upthrust of said knife, thereby to break said seam and open said structure by dividing the same substantially evenly along a length of said line overlying the fluting last-mentioned so that the seam-structure parts 35 thus divided can be diverged without breakdown thereof to expose said fluting for reversal thereof to form a pouring spout; both said seam-structure parts when thus diverged being resiliently urged toward their original parallelism be- 40 cause both include one of said web components and one of said side walls always maintained in close flatwise contact.

5. A container incorporating a blank structure 45 folded to provide a rectangular bottom wall and similar side and end walls for the container, with said end walls inwardly fluted at their tops to make the container substantially triangular in end elevation at its top and to give the container a satchel-top; said flutings and the upper por- 50 tions of said side walls presenting a filling mouth along the entire length of said top; said filling mouth having a closing flap at one side thereof; said blank structure including a builder sheet of heavier material, and a sealer sheet of lighter 55 material; said builder sheet forming said bottom, side and end walls and thereby establishing said satchel top, and said sealer sheet being shaped and arranged to run around the upper marginal portions of said walls and to follow said flutings 60 while extending its own marginal portions above said filling mouth, whereby when said mouth is closed by downfolding and securement of said flap the upwardly extending marginal portions of the sealer sheet are downbent and folded on and drawn tight over edge portions of said filling mouth for disposal under the downfolded flap to hermetically seal said satchel-top.

6. The container defined in claim 5, wherein said flap is of readily severable material so that by insertion and upthrust of a knife inserted within one of said flutings said flap can be partially severed and said mouth correspondingly opened for partial dispensing of the contents of the container, and wherein there are means slid-

able along the crest-line of the satchel-top to close the opening established by such severing and thus to temporarily reseal the container all over the filling mouth after such dispensing.

5. 7. A satchel-type self-sustaining container folded up from a blank of a comparatively stiff and somewhat resilient material such as press-board to have side walls mutually converging toward the top line of the container and end walls each having an inwardly directed fluting at its top; said container having means for sealing the same along said top line thereby to couple tightly together the upper portions of said flutings and said side walls to make a 10 rigidifying rib structure for the container incorporating a filling mouth and a closing seam therefor; said sealing means including a sealing element readily severable along said line, by inserting a knife within such a fluting from the exterior of the sealed container and by upthrust of said knife, thereby to break said seam and partially reopen said mouth by dividing the rib structure where it overlies the fluting last-mentioned so that said rib structure can be diverged 15 without breakdown of the container to expose said fluting for reversal thereof to form a pouring spout; said sealing means further including a sealer sheet of lighter material than said blank, said sealer sheet being shaped and disposed to lie at least partially within the container in the vicinity of said rib structure and to participate 20 in the formation of said rib structure by foldings of marginal portions of said sealer sheet about edge portions of said blank incidental to the establishment of said rib structure.

35 8. A container comprising a two-ply rectangular blank including a form-defining relatively rigid sheet, and a pliable sheet having its outer margin extending beyond the boundary edge of the first sheet and coacting therewith, said sheets having therein registering fold lines and being foldable thereon to provide a rectangular bottom, opposed end walls having at their top portions inwardly turned flutings, opposed side walls having the ends of their top portions disposed opposite said flutings, and inwardly folded triangular sections disposed between the respective end walls and side walls, said sections having their top portions disposed adjacent the second-mentioned portions whereby to provide a 40 filling mouth between said flutings, said margin being continuous and disposed above said edge to provide a guide for the mouth.

45 9. A container comprising a two-ply blank including an outer relatively rigid sheet having a rectangular body or main part, a lining and sealing sheet cooperating with the first sheet and having its outer margin extending beyond the outer boundary portion of said body, said sheets having therein registering score lines and being folded thereon to provide a bottom, opposed end walls having inwardly closed fluted tops, opposed side walls having the ends of their upper portions disposed adjacent said tops, inwardly folded triangular sections disposed between the respective end and side walls, said sections having their upper portions disposed between the first upper portions and said tops, said boundary portion being continuous along said tops and said upper portions, said extended margin being turned onto the upper portion of one of said side walls along the length thereof, and a flap extending from the upper portion of the other side wall, said flap being bent over said margin and engaged thereon in sealing relation.

10. A container comprising a pressboard sheet having therein score lines and being folded thereon to provide a rectangular bottom, side walls rising from the longer boundary sides of said bottom, end walls rising from the shorter boundaries of said bottom, said walls having their top portions disposed above and parallel with the longitudinal central line of said bottom, the tops of said end walls being fluted and closed inwardly between the ends of the tops of said side walls, and opposed triangular sections disposed between the respective end and side walls, said sections having bottom points disposed at the corners of said bottom, said sections having therein notches at the points opposite the first points, the boundary edges of the notches being vertically disposed, and the edges of the opposed notches being disposed at the centers of the tops of said side walls.

15 11. A container comprising a two-ply blank including a form-defining stiff sheet having a body or main part, a lining sheet having its outer margin extending beyond the outer boundary portion of said body, said sheets having therein registering score lines and being folded thereon to provide a rectangular bottom, side walls rising from the longer boundary sides of said bottom, end walls rising from the shorter boundaries of said bottom, said side walls having their top portions disposed above and parallel with the longitudinal central line of said bottom, the tops of said end walls being fluted and closed inwardly between the ends of the tops of said side walls, and opposed coacting pairs of triangular sections disposed between the respective end and side walls, each opposing pair of said sections having point portions of the lining sheet thereof overlapped at the top centers of said side walls, the corresponding point portions of the stiff sheet being notched or cut away, the boundary 20 edges of the notches being vertically disposed and opposed edges of said notches being practically abutting at said top centers, said extended margin being bent over and downwardly onto the outer face of the top of one of said side walls, and a flap extending from the top of the other side wall, said flap being bent over the downwardly turned margin in sealing relation therewith.

25 12. In combination, a sheet of relatively rigid material having therein score lines and being foldable thereon to provide an outer form-defining container member including a rectangular bottom; coacting side walls, end walls and interposed sections rising from said bottom and having their top portions forming a mouth above the longitudinal central line of said bottom; a lining sheet larger than the first sheet and disposed in attached relation therewith, said lining sheet having its outer margin extending substantially 30 beyond the first sheet; and means for sealing said mouth, said means including said margin.

35 13. A container having an outer sheet of press-board forming practically flat side walls, said walls having their top portions inclined inwardly 45 to form an elongate mouth, end walls having their top portions folded inwardly and disposed flatwise between the ends of the first portions; a pliable sheet larger than the first sheet and forming a complete lining therefor, said lining 50 sheet having its outer margin extending above said portions; and means for sealing said mouth, said means including said margin, the latter being bendable laterally and downwardly onto the top of one of said side walls, and a flap ex-

tending from the top of the other side wall and being adhesively attachable over said margin.

14. A container comprising in combination a body of fibrous material including opposed rectangular side walls having their top portions inclined inwardly to form an elongate mouth, end walls having their top portions folded inwardly and being disposed flatwise between the first portions, said walls having the upper margins of said portions bendable laterally and downwardly onto the top part of one of the side walls, said margins forming a closure rib, said material being severable and the inwardly folded portions forming opposed recesses below the ends of the rib, said recesses adapted to receive a severing instrument, and a metal member centrally gripping a small portion only of said rib and the top part of the opposite side wall, so that an instrument may be inserted in one of said recesses, whereby to partly sever the rib so as to provide an opening, said member being adapted to stop the instrument.

15. A closure for a container comprising a sheet of pressboard which is foldable to provide an outer member including opposed side walls having their top parts forming an elongate mouth, and a lining sheet foldable with the first sheet; said closure including an outer margin of the lining sheet, said margin being extended beyond the top portions of said parts, said margin being folded laterally and downwardly onto one of said parts to form a rib thereon; a sealing clip having one side engaging the other opposite part, and an opposite side engaging said rib, said latter side having an inturned flange disposed below said rib.

16. A closure for a container comprising a sheet of fibre board which is foldable to provide an outer form defining member including opposed side walls having their top portions forming an elongate mouth, and a lining sheet foldable with the first sheet and having its outer margin extending therebeyond; said closure including said margin which latter is extensible above said portions, said margin being folded laterally and downwardly onto one of said portions, a flap extending from the opposite portion and being turned downwardly over said margin whereby to form a rib; and a sheet-metal clip of U-shaped cross-section, said clip having one of its legs engaged against the last-mentioned portion, the other leg of said clip being engaged against said rib, and a flange turned inwardly from the last-mentioned leg, said flange being engaged below the bottom of said rib.

17. A severably openable container comprising two side walls having substantially engaged top portions, there being a flap extending from one portion and engaged on the outside of the other portion, said portions and the flap forming a rib, end walls including top portions which form re-entering pockets between the first portions, so that the flap may be severed above at least one of the pockets to open the container, and a metal clip slidably embracing said rib, whereby the clip may be moved to a predetermined position to limit the severing of said flap.

18. A container according to claim 17, wherein the metal clip is substantially as long as the top portions of the side walls, said clip adapted to form a hand grip for the container.

19. A container according to claim 17, wherein the clip is U-shaped in cross-section, one of the legs of the clip having extending completely along the inner face of the bottom thereof an

inwardly bent edge portion, whereby to engage below the edge portion of the flap, said clip adapted to form a hand grip for the container.

20. A severably openable container of satchel type comprising opposed end walls having at their tops accordion folds, the top edge portions of said folds being closed together or adjoining and there being outwardly facing recesses below said portions, opposed flat side walls having their top parts closed inwardly on said edge portions, a closure flap extending from one of said parts and being adhesively attached to the opposite part, so that the flap may be severed above one of said recesses substantially between two of said adjoining portions; and a pull cord attached at the innermost end of one of said recesses to the associated fold, whereby the latter may be pulled out to form a pouring opening.

21. A severably openable container of satchel type comprising an outer sheet of paper-board including opposed end walls having at their tops accordion folds, the top edge portions of said folds being in adjoining relation and there being outwardly facing recesses below said portions; opposed side walls having their top parts closed inwardly on said edge portions, a flap extending from one of said parts and being folded over said adjoining portions and adhesively attached on the opposite part, so that the flap may be severed above one of the recesses substantially between two of said adjoining portions; and a pull cord having its inner end attached at the innermost end of one of said recesses to the associated fold, whereby the other end of the cord may be manually grasped to put out the last-mentioned fold, so as to also extend the side walls thereat and form a pouring spout.

22. A severably openable container comprising a two-ply rectangular blank including a form-defining relatively rigid foldable sheet, and a pliable sheet having its outer margin extending substantially beyond the first sheet; said blank providing a rectangular bottom, end walls having at their top portions accordion folds, the top edge portions of said folds being in adjoining relation and there being outwardly facing recesses below the edges of said portions, opposed side walls having their top parts closed inwardly on said portions, a flap extending from one of said parts and being passed over and close to said edges, said flap being adhesively attached on the opposite part to form a closure; said flap being severable over and substantially between two of the edges, and a pull cord including a free outer end and having its opposite end attached at the innermost end of one of said recesses to the associated fold, whereby said free end may be manually grasped to pull out the last-mentioned fold, so as to also extend the side wall parts thereat and form a pouring opening.

23. A satchel type container constructed of a compound rectangular blank comprising a lining sheet, and an outer relatively stiff form-defining sheet comprising opposed side walls, and opposed end walls including sections which have their top portions accordion-folded, said sections having continuous with the sides thereof infolded web components, said components being also continuous with the end portions of said side walls, said components having in their four outer corners angular notches, so that when said components are folded inwardly the associated boundary faces of each notch may register vertically, the registered faces of the opposing com-

ponents being disposed in abutting relation on the transverse vertical central plane of the container, the top portions of said components being horizontally disposed on the outer sides of the top portions of the accordion folds; said side walls having their top parts engaged flatwise against the top horizontal portions of said components, and a closure flap extending from one of said parts and being passed closely over said horizontal portions, said flap being adhesively attached on the opposite top part.

24. A container constructed of a compound blank comprising an outer relatively stiff form-defining sheet including a rectangular body part, and a rectangular inner lining sheet cooperating with said part and having an outer margin extending therebeyond; said sheets providing a rectangular bottom, side walls rising from said bottom and having their top portions adjoining, end walls rising from said bottom and having their top parts fluted and closed inwardly between said portions, said margin being extended beyond said portions and beyond the tops of the fluted parts so as to form a sealing member, said member being folded over onto the outer surface of one of said portions, and a flap connected with the other portion and having a greater longitudinal dimension than that of said margin, said flap being folded over the folded margin and being sealed at its transverse end part on said surface.

25. A container comprising a bottom and having opposed side wall folds, opposed end wall folds, triangular web components connecting said folds and being folded inwardly therebetween, said side folds having their top portions adjacently disposed, the end folds having their top parts accordion folded and being disposed between said portions; and a flap connected with one of said portions and being passed over the top edges of said components and said accordion folds said edges being in adjoining relation whereby to provide a closure, said flap having sealing engagement with the outer surface of the opposite portion.

26. A pouring container comprising opposite side walls; an intermediate wall connecting the side walls and inwardly turned between said opposite walls to form a recess extending to the exterior of the container; a closure flap of sever-

able material extending from end to end of, and attached to one of said opposite walls and passed over the free edges of the intermediate wall and secured to the other opposite side wall and adapted to be easily severed at the portion over the recess, whereupon the inwardly turned intermediate wall may be pulled outwardly to form a pouring spout; and a pull means secured to the intermediate wall near the inner part of the recess for pulling said wall outwardly.

27. A pouring container comprising folded first and second opposite walls; intermediate walls connecting said opposite walls, each intermediate wall being inwardly turned at its top part between said opposite walls to form a recess extending to the exterior of the container and having edge portions adjacent to each other; a flap of severable material extending from end to end of, and attached to, said first opposite wall and passed over the edges of the intermediate walls and secured to the top margin of the other opposite wall from end to end of the latter; said flap being longitudinally severed immediately over said edges of one of said recesses to allow the adjacent inwardly turned intermediate wall to be pulled outwardly to form a pouring spout, the remaining portion of the flap being unsevered; said recess at the severed end of the flap being open to the exterior adjacent to the uppermost part of the inner face of the flap at said severed end.

28. A pouring container comprising folded first and second opposite walls; intermediate walls connecting said opposite walls, each intermediate wall being inwardly turned at its top part between said opposite walls to form a recess extending to the exterior of the container and having edge portions adjacent to each other; a closure flap of severable material extending from end to end of and attached to said first opposite wall and passed over the edges of the intermediate walls and secured to the top margin of the second opposite wall from end to end of the latter; said flap being severable immediately over said edges of one of said recesses so that the adjacent inwardly turned intermediate wall may be pulled outwardly to form a pouring spout suitable for pouring fine material.

DURYEA BENSEL.
